UNITED STATES PATENT OFFICE

2,428,852

SAND BLENDER

William P. Muir, Toronto, and Robert H. MacInnes, St. Catharines, Ontario, Canada; said MacInnes assignor to said Muir

Application December 18, 1943, Serial No. 514,868

3 Claims. (Cl. 209—92)

1

This invention relates to improvements in machines for blending sand, clays or other pulverized materials so that all lumps or coherent masses will be broken down and foreign matter, such as stones, bits of wood or metal, will be removed therefrom.

The principal object of the invention is to provide a machine which may be operated at high speed to agitate and comb the pulverized materials so that they will be thoroughly mixed and discharged therefrom to form a smooth and uniformly pulverized mass ready to be used in the fashioning of moulds for metal castings or for being moulded to form cast products or for any other purpose where a uniformly pulverized condition of a product is desired.

A further object of the invention is to provide a means for mixing and agitating the pulverized material which will be highly resistant to wear and abrasion and which will deliver the mixed material in a uniform manner and condition.

The principal feature of the invention consists in providing a travelling belt for machines of the class described in which the surface is formed of rubber or rubber composition with spaced-apart projections capable of being drawn through a mass of pulverized material to pick out and comb the material, to break down coherent masses and to force the pulverized material between the separate flexible fingers of an obstructing curtain arranged adjacent to said belt at the discharge end of the machine.

In the accompanying drawings Figure 1 is a longitudinal vertical part mid-section through a sand blending machine constructed in accordance with this invention.

Figure 2 is a transverse sectional view taken through the machine on the line 2—2 of Figure 1.

Figure 3 is a plan view of one form of a belt devised for use in this machine.

Figure 4 is a plan view of the preferred form of belt.

Figure 5 is a cross sectional view of the belt illustrated in Figure 4.

Figure 6 is an enlarged longitudinal sectional view of a portion of the belt, such as shown in Figure 4.

In the handling of moulding sand in foundries, when moulds are broken down and castings are removed therefrom, a certain amount of the sand has become burned and lumps and coherent masses are encountered, and it is frequently found that such masses contain particles of metal broken from a casting or from a gate,

2

and so also pieces of stone, wood or other foreign matter may get into the sand.

It is important that the sand that has been used should be broken down and free from all lumps and pieces of foreign material should be removed therefrom, and the pulverized material should be thoroughly blended so that clays and sand will be thoroughly mixed wherever such are present.

10 Sand blenders have been commonly used and these utilize an endless belt which forms the bottom of a hopper, and the belt which has been used has been formed of leather or fabric studded with nails or spikes to act as combing media to engage and break down the lumps of coherent material found in the mass.

15 The present invention proposes to utilize substantially the same construction of machine as has been hitherto used but proposes an entirely new form of belt for combing, separating and discharging the pulverized material.

20 As illustrated in the accompanying drawings a portable frame 1 is mounted on wheels 2 and carries a steep angularly disposed platform 3 which rises from the rear end of the machine.

25 A pair of drums 4 and 5, mounted on shafts 6 and 7 respectively which are journaled in the side frame of the machine, support an endless belt 8 which extends around the perimeters of the drums and is preferably formed of a flat body structure 9 which is suitably reinforced with fabric or woven wire 10, and at either side the belt is formed with upstanding flanges 11. Between the flanges are arranged transverse rows of upwardly projecting teeth or studs 12, which as shown in Figures 4, 5 and 6, are of rectangular form and preferably have the forward edges 13 extending right angularly from the face of the belt, while the rear walls 14 slope from the face 40 of the belt upwardly to the rectangular top.

30 The side walls of each of the toothed members 12 are preferably slightly sloped to enable the belt to be cleared from the mould in which it is made, and the teeth of alternate rows are preferably 45 staggered, as illustrated particularly in Figure 4, so that the spaces between each pair of teeth in one row are obstructed by the teeth in the next succeeding row. This staggered arrangement of the teeth permits the teeth to engage the mass of sand 15 which is placed on top of the belt between the sloping side walls 16 of the machine. These sloping side walls extend close to the edges of the side flanges 11 of the belt and sand that is placed between the side walls falls in between the 50 side flanges 11 and is engaged by the alternate 55 side flanges 11 and is engaged by the alternate

staggered rows of teeth 12 as the belt is operated to move in an upward direction on the underside of the frame.

The result of this upward movement of the belt, which is driven in a suitable manner by a motor 17 mounted on the underside of the platform 3, is, the succeeding staggered rows of fingers comb through the lower strata of the mass of sand placed thereon between the side boards 16 and break all lumps and cohering masses and thoroughly mix the particles of material, whether they be abrasive sand or sand mould or even clay, and the engagement of the teeth 12 with particles of stone or wood or other foreign matter, which may get into the sand mass, forces the same outwardly so that they work back to the lower inclined end where the sand is held by the tiltable back board 18.

Such coarse particles of material, stone, bits of metal or wood may be released from the mass above from time-to-time in the operation of the machine by tilting the board 18 to raise the bottom edge from the belt, allowing the larger particles to fall clear of the belt.

As the combing teeth 12 engage and break down the mass of sand placed in the machine they carry a quantity of the broken-down material in front of each of the teeth, and the material thus carried along is projected with considerable impetus from the fast revolving belt.

In order that large masses of the pulverized material shall not be carried forward and delivered from the belt unequally, a screen member 19 is arranged at the upper end of the machine. This is adjustable and has mounted on its lower edge a depending curtain 20 which is preferably formed of a sheet of rubber having its lower edge cut to form a plurality of fingers, and these fingers being flexible yield to the material being carried by the belt, permitting a certain height of material to be carried by the toothed belt past the barrier. The flexible rubber fingers act as a comb to spread out the top surface and keep it uniform. Thus the delivery from the machine is in the form of a uniform sheet of pulverized material which is directed by an adjustable chute 21.

The main feature of the idea rests in the formation of the rubber belt with a plurality of teeth arranged in rows in offset staggered relation. A modified form of this idea is illustrated in Figure 3 in which the teeth 22 are of diamond-shaped form and divide the material under which they are passing into separated streams which work back and forth to cause effective intermixing of the particles to blend the mass.

The device has been found in operation to be extremely practical and it is a very distinct advance over any form of belt hitherto used in sand blenders.

The device is described as being used particularly with moulding sand but it will be understood that it may be used with other materials of pulverized or granular form which it is desired to blend into a uniform dry mixture.

What we claim as our invention is:

1. In a sand blending machine, the combination with a frame and an angularly disposed sand receptacle, rollers arranged at the opposite ends of said frame beneath said receptacle, of an endless rubber belt mounted on said rollers and forming a bottom for said sand receptacle and having moulded integrally therewith on its outward face a plurality of teeth arranged in spaced-apart parallel rows, the teeth of each row being spaced apart and arranged in longitudinally staggered relation to the teeth of adjacent rows to effect a forceful lateral dispersal of sand by each tooth as the belt rotates.

2. In a sand blending machine, the combination with an angularly disposed frame, a hopper having inclined side walls, and transverse rollers mounted at each end of the bottom of said hopper, of a fabricated rubber belt having longitudinal side flanges extending below said hopper side walls, and rows of regularly transversely spaced teeth formed integral therewith, the teeth of each row being arranged in longitudinally staggered relation to the teeth of adjacent rows, each tooth in each row overlapping the space between the teeth in the adjacent row to effect a dispersal of the sand as the belt rotates.

3. In a sand blending machine, the combination with a frame and a sand receptacle mounted in an inclined position thereon, of rollers arranged transversely of said frame beneath said receptacle, an endless rubber belt mounted on said rollers and forming the bottom for said receptacle, said belt having upwardly projecting side flanges, and rows of transverse rectangular-shaped teeth moulded integrally therewith and spaced apart, the teeth of each succeeding row being staggered in relation to the teeth in a preceding row, said teeth having flat front surfaces arranged perpendicular to the surface of the belt and bevelled back surfaces.

WILLIAM P. MUIR.
ROBERT H. MACINNES.
